PLATE-STOP.

1,283,403.

Specification of Letters Patent. Patented July 17, 1917.

Application filed November 4, 1916. Serial No. 129,422.

To all whom it may concern:

Be it known that I, OSCAR ROESEN, a citizen of the United States, residing at New York city, county of New York, and State of New York, have invented certain new and useful Improvements in Plate-Stops, fully described and represented in the following specification and the accompanying drawings, forming a part of the same.

This invention relates to certain improvements in plate-supports for printing machines.

In printing machines, and particularly rotary machines in which the form-carrying member is a cylinder, stops or bars are provided extending longitudinally of the cylinder against which one edge of the plate abuts, the plate then being clamped in position by the side clamps and held in position against the bar or abutment by the rotation of the cylinder. It frequently happens, through carelessness of the pressman in putting the plate on the cylinder, and particularly where the cylinder is in a dark or dim location, that the edge of the plate will lap over on top of the bar or stop, the plate being then clamped in this wrong position. This results, in many instances, when the cylinder goes on impression, that is, is brought into coöperation with its impression cylinder, that the edge of such cylinder is broken, thus damaging the cylinder.

It is an object of the invention to produce an improved construction of plate cylinder or other plate-support, in which these plate-stops or bars are employed, in which the bar will be so mounted that it may have a limited vertical movement with respect to the cylinder or other support, so that if accidentally a plate is so positioned on the cylinder as to lap over onto the bar, the pressure of the plate on the bar, when the plate goes on impression, will cause the bar to move toward the surface of the plate and will thus prevent the cylinder from being damaged. The impression will, of course, be in the wrong place on the sheet or web, which is a signal to the pressman that a plate is wrongly positioned and he can stop the press and correct the error, and the press is not damaged.

It is a further object of the invention to produce such a construction which shall be simple, efficient for the purpose intended, and easily and quickly assembled.

In the drawings are shown various ways of effecting the desired results. In these drawings—

Figure 1 is a sectional elevation, partly broken away, showing one construction which may be employed for the purpose;

Fig. 2 is a cross section taken on the line 2—2 of Fig. 1;

Fig. 3 is a sectional elevation, partly broken away, of a modified form of construction which may be employed;

Fig. 4 is a cross section of the same, taken on line 4—4 of Fig. 3;

Fig. 5 is a sectional elevation of a further modified form, which may be used for the purpose, and

Fig. 6 is a cross section taken on the line 6—6 of Fig. 5.

Referring now to these drawings, the invention has been shown as employed in a rotary machine in which the form-carrying member of the printing couple is a cylinder, but it will be understood that the invention might be used in other relations.

Referring now first to Figs. 1 and 2, the cylinder C is illustrated as provided with the usual slot 2 extending horizontally of the cylinder and substantially the length thereof. In this slot is mounted the plate-stop or bar 3, against which one edge of the plate P may abut, as shown in the drawing, this stop acting as an abutment to hold the plate in position, together with the usual side clamps employed (not shown). In accordance with the invention, the plate bar or stop 3 is mounted so that it can have a limited movement in the slot 2, so that if the plate is accidentally placed so as to lie on top of the bar, the bar will move down into the slot and prevent the edges of the plate from extending so far above the surface of the cylinder that the press would be damaged when thrown on impression, and, furthermore, in constructions embodying the invention in its best form, the plate stop or bar will be resiliently or yieldingly mounted in the slot. While this may be effected in various ways, in the particular construction shown the cylinder C is counterbored to form holes 4 extending below the slot 2 above referred to, a suitable number of these holes 4 being provided to effect the purpose desired. In these holes are arranged springs 5 taking against the bottoms of the slots 4 and the underside of the plate stop or bar 3,

this stop or bar thus being yieldingly mounted so that it will be forced down into the slot 2 if a plate is accidentally positioned so as to lap over onto it.

5 In its normal position, and as shown, the stop or bar 2 extends above the surface of the cylinder a sufficient distance to form a suitable stop or abutment for the plate, but not a distance as high as the thickness of the 10 plate, so that impression is not interfered with when the form or plate cylinder is thrown into printing relation with the impression cylinder. While this may be effected in various ways, the bar is held in 15 the groove against the tension of the spring by headed screws 6 which take against flanged sockets 7 suitably located in the bar, a suitable number of these sockets and screws being provided, which number may be varied.

20 Referring now to Figs. 3 and 4, a modified form of securing the bar in the cylinder is illustrated, and a somewhat modified form of bar. As usual, the bar 3 is formed at one side with a beveled slot 8, this being provided to permit a plate to be used which has its straight or longest edge beveled. In 25 this construction the springs 5 are held in the holes 4 bearing against the bottom of the bar, as shown. The bar is, however, provided with small grooves 9 cut into its sides, against which take a portion of the heads of headed screws 10, the other part of the screw-head taking in a slot cut in the 30 surface of the cylinder. As shown in Fig. 4, furthermore, these securing screws 10 extend lengthwise of the cylinder, but are, if desired, and as shown in Fig. 4 in dotted lines, in staggered relation to the sides of 35 the bar, that is to say, on alternately opposite sides of the bar.

40 Referring to Figs. 5 and 6, a somewhat modified construction of plate-stop, and means for securing it in position on the cylinder, are illustrated. In the construction here shown the stop is in the form of a number of small stops 12 which project, as shown in Fig. 6, a sufficient distance above the surface of the cylinder to form an effective 45 plate-stop or abutment. These stops are what may be termed H-shaped in cross section, and are mounted in counterbores 13 in the cylinder. Springs 14 take against the lower surface of the web 15 of the H and 50 surround the stem of a screw 16, by which

the stops are held in correct position in the cylinder by the head of the screw taking against the upper surface of the web 15 of the H, the stops being free to slide vertically in the counterbores 13.

60

65 It will be seen that by the construction above described a very simple and efficient arrangement has been provided for so mounting the plate-stops or bars in the machine that if a plate is accidentally misplaced in putting it on a press, the bar will yield and prevent damage to the cylinders.

65

70 While the invention has been shown in its preferred forms, it will, of course, be understood that other specific forms for effecting the purposes of the invention might be designed, which would embody the invention, and the invention, therefore, is not limited to the specific constructions shown and described.

75

What is claimed is:

1. The combination of a printing plate support and a bar or stop against which a plate may abut when positioned on the support, said bar or stop being mounted on the support so as to have a yielding movement relatively thereto.

80

2. The combination of a printing plate support, a groove or slot in the support, and a bar or stop mounted in the groove against which a plate may abut when positioned on the support, said bar or stop being mounted so as to have a vertical movement in the slot under the pressure of a plate.

85

3. The combination of a printing plate support, a groove or slot in the support extending longitudinally thereof, a bar or stop in the groove against which the plate may abut when positioned on the support, and springs against which said bar or stop abut and which permit the bar to have a vertical 90 movement in the slot under the pressure of a plate.

95

4. The combination of a support having a curved plate-supporting surface, a groove or slot in the support, a bar or stop in the groove against which a plate may abut when positioned on the support, recesses in the support, and springs in the recesses under the bar for permitting the bar to have a vertical movement in the slot under the pressure of a plate.

100

105 In testimony whereof, I have hereunto set my hand.

OSCAR ROESEN.
